UNITED STATES PATENT OFFICE.

HUGH I. JORDAN, OF STAUNTON, VIRGINIA.

VALVE LIFTER.

Application filed November 18, 1922. Serial No. 601,754.

To all whom it may concern:

Be it known that I, HUGH I. JORDAN, residing at Staunton, Virginia, a citizen of the United States, have invented certain new and useful Improvements in Valve Lifters, of which the following is a specification.

My invention relates to tools for use in compressing the seating springs of poppet valves of internal combustion engines to enable the ready removal of the valves, and my invention is embodied in that form or type of tool which comprises two members one for engaging the valve head and the other for engaging the spring washer and such a connection between the two members as will permit the movement of the spring engaging member in the direction to compress the spring. My invention in what I consider its best embodiment gives the advantages of ability to use the same tool with the valves of a variety of engines, rapidity of manipulation so that a valve may be removed in short time, and ease of manipulation. My invention consists in whatever is described by or included within the terms or scope of the appended claims.

In the annexed drawings:

Fig. 1 is a perspective view of a tool embodying my invention, and Fig. 2 is a side elevation, the full lines showing the position of parts when the tool is applied and the dotted lines showing their position when the valve spring has been compressed.

Referring in detail to what is shown in the drawings, the member of my tool which is engaged with the top of the valve head and which forms the support upon which the movable spring compressing member moves comprises a shank, 10, that may be a flat metal bar which at the valve engaging end is pointed to engage the usual hole in the top of the head, and at the other end is provided with a handle, 11, for the comfortable engagement, say the left hand of the workman to place and hold the tool in position. The spring engaging member, 12, is substantially C-shaped so that with its lower spring washer engaging end thrust beneath such washer it will clear the manifold, and near its upper end is pivotally connected with a hand lever, 13, which at one end by a pivot, 14, is fulcrumed on the support, 10, and at its other end has a hand-grip, 15, to enable the workman comfortably to press upward on the lever, and thereby move upward the spring washer engaging lower end of the member 12. Preferably the member, 12, is made of two similar flat metal bars, which lie one against the other throughout their extent, except at the lower end of the member where they diverge into a V-shape so that they may straddle the spring washer and each fork or arm of the V has an inturned flange, 16, to catch underneath said washer. At the points of divergence of the forks or arms is a bolt 17, by which to adjust the distance between the arms to suit washers of different diameter, normally the forks tending to spring apart from the natural spring of the bars that form the member, 12. At the point of connection of the operating lever, 13, with the member, 12, the latter passes between the two parts that form the member, 12, so that the connection between the lever and the member, 12, is a single link, and not a pair of links which would add to the cost and weight of the tool.

From the pivot, 18, which connects the lever, 13, and member, 12, the latter is extended upward and at the extremity thereof by a pivot, 19, one end of a link, 20, is connected, the other end being connected by a pivot, 21, to support 10, and thus the support, 10, and the member, 12, are so connected together that they are readily maintained in relative position, and thus convenience of handling the tool is promoted. There is but a single link, 20, in the interest of producing metal and thus saving cost and weight. The link, 20, is also utilized as a part of a latch device to secure the spring compressing member, 12, in spring compressed position so as to leave the hand of the workman free to remove the pin or other device on the valve stem when it has been freed from the pressure of the spring. Said latch device comprises a rack bar, 22, which is pivoted to the support, 10, and a stud, 23, on the link, 20, with which the teeth of the rack may engage, the rack having a hand member, 24, which extends alongside of the support handle, 11, so that the hand grasping the handle, 11, may readily release the rack from the stud, 23, with which it is yieldably engaged by a spring, 25, interposed between the support, 10, and the rack member, 24. The rack engaging stud, 23, may be one end of a loop, 26, that confines

the rack, 22, in position while allowing it enough freedom to swing into and out of engagement with the stud, 23.

It is important that when the spring compressing member, 12, is moved in the direction to compress the spring that the forks or arms be kept in contact with the washer. I maintain such engagement and assure it by producing a tendency of the washer engaging arms to move in the opposite direction from that which would slip them from beneath said washer, and I accomplish that result by making the link between the pivots, 14, and 18, longer than the link between the pivots, 19, and, 21, so that when the operating lever, 13, is moved upward from the full-line position of Fig. 2 to the dotted line position of Fig. 2, the pivot, 18, between the lever, 13, and the member, 12, will move towards the support member, 10, and thus the spring compressing member, 12, will be moved or tend to move to carry its washer engaging arms into more secure contact with the washer.

It is important that the line of thrust of the washer engaging portion of the member, 12, shall be coincident with the axis of the valve stem, and the point of bearing contact of the support member, 10, on the valve head in order to prevent slipping of the spring compressing member, 12, off the washer. To enable this condition to exist even when dealing with valves whose stems stand at an angle, I provide for change of the point of connection of the pivot, 18, between the lever, 14, and the member, 12, the latter having several holes, 26, into any one of which the pivot, 18, may be placed so as to vary the angle of the support, 10, with reference to the spring pressing member, 12.

What I claim is:

1. A valve lifting tool comprising a support member having a handle at one end

and adapted to engage a valve head, a spring compressing member, a lever having a handle and pivotally connected to both of said members to form a link connection between them, a second link connection between said members, the linkage between the two members being arranged to cause a tendency of the spring compressing member to remain in position to act upon the spring, the spring engaging part of the compressing member terminating in a free extremity which by such tendency is prevented from moving towards the valve stem.

2. A valve lifter comprising a support member having a handle at one end and adapted to engage a valve at the other end, a spring compressing member, the latter being formed of similar side by side bars that diverge to provide supporting arms adapted to straddle the valve stem, a pair of links connected with the support and the spring compressing member at different points, one of said links passing between the two parts that form the spring compressing member, means to move the spring compressing member on its pivotal connection with the support member, and a latch device between the support member and one of said links.

3. A valve lifter comprising a support member having a handle at one end and adapted to engage a valve head, a spring compressing member terminating in a free end that engages the spring, a pair of links pivotally connecting such members, the link pivots being so disposed that at all times during a spring compressing movement of the compressing member its free end will tend to move in a direction opposite that for the withdrawal of the same from the spring.

In testimony whereof I hereunto affix my signature.

HUGH I. JORDAN.
